UNITED STATES PATENT OFFICE

JAMES E. WHITMILL, OF HAYNESVILLE, LOUISIANA

VALVE SEAT GRINDER

Application filed May 29, 1930. Serial No. 457,278.

The object of the invention is to provide a device particularly adapted for refacing the valve seats of engines, particularly such as those employed in oil fields, so that it will not be necessary to remove the seat for facing by machinery, as is customarily the case; to provide a grinder which may be actuated by a hand tool, such as the conventional brace, and which will effectively maintain its position of perpendicularity with reference to the plane of the seat; and to provide a device of this character which is of simple form and therefore susceptible of cheap manufacture and low marketing cost.

With this object in view, the invention consists in a construction and combination of parts of which a preferred embodiment is illustrated in the accompanying drawings, wherein:

Figure 1 is a vertical sectional view through the valve chamber of an engine, showing the invention in operative position therein.

Figure 2 is a top plan view of the invention.

Figure 3 is a diametrical sectional view on the plane indicated by the line 3—3 of Figure 2.

The invention comprises the grinding head 10 of disk form and constructed preferably of cast iron, although it may be made of any acceptable material. Formed integrally with the grinding head at the center of the latter, is the shank portion 11 at the upper end of which is disposed the star shaped member 12 of which the arms 14 are uniformly spaced angularly and have a slightly greater radial extent than the grinding head. The tang 15 extends axially from the upper side of the star shaped member and constitutes the means by which the device may be actuated, as by the conventional hand brace, or similar tool.

Against the under face of the grinding head 10 is disposed the grinding disk 16 which may be of carborundum, emery or other suitable abrasive. To preclude relative angular or turning movement between the grinding disk and the head, the former is secured to the latter by fasteners 17, which

are preferably bolts extending through the disk and head and disposed on diametrically opposite sides of the shank 11. The grinding disk 16 has a central clearance opening for the pilot 18 which extends from the lower face of the grinding head at the center of the latter through the grinding disk.

The grinding disk on its lower peripheral edge is bevelled, as indicated at 19, in correspondence with the correct bevel of the valve seat to be ground.

When the device is employed to grind a valve seat, as is disclosed in the drawings, the bevelled grinding edge 19 of the disk 16 is properly disposed on the valve seat by reason of the pilot 18 and the star shaped member 12, the ends of whose arms abut the surrounding cylindrical wall of the valve chamber. The actuating tool being engaged with the tang 15, the whole device may then be rotated and, being held in proper position by the pilot and star shaped member, the grinding disk will effectively true the seat.

The star shaped member, it will be noted, consists of an odd number of arms, preferably three, so that no two may lie in the same diametrical line which would likely prevent their centering function with free turning movement.

The invention having been described, what is claimed as new and useful is:

A valve seat grinder comprising a grinding head of slightly less diameter than the valve chamber to permit its freely entering the latter, a star-shaped member having a shank portion by which it is integrally connected with the head but axially spaced from the same, the arms of the star-shaped member being of a radial extent to bring them in contact with the wall of the valve chamber, a grinding disk carried on the under face of the head, and a centering pilot protruding from the under face of the head for sliding engagement with the valve-stem guide.

In testimony whereof he affixes his signature.

JAMES E. WHITMILL.
